(57) CLAIM

The ornamental design for a retainer clip, as shown and described.

DESCRIPTION

FIG. 1 is a perspective view of a retainer clip shown in a tensioned position showing my new design;

FIG. 2 is an exploded perspective view thereof showing the retainer clip in a relaxed position;

FIG. 3 is a top view thereof;

FIG. 4 is a bottom view thereof;

FIG. 5 is a rear view thereof;

FIG. 6 is a front view thereof; and,

FIG. 7 is a side view thereof, the opposite side of which is a mirror image.

The broken lines showing environment in the drawings are for illustrative purposes only and form no part of the claimed design.
